MAGNETIC SEPARATING MACHINE

Application filed August 17, 1929, Serial No. 386,691, and in Germany October 15, 1928.

My invention relates to machines for dressing and classifying ores and metallurgical waste products such as slags, sweepings and other residues by separating through magnetic force the more valuable parts from those not responsive to magnetism.

The invention relates more especially to an improved feeding device for magnetic separating machine for the purpose set forth and of the type diagrammatically shown in the drawing in which a hollow cylindrical shell of diamagnetical material rotate on a horizontal axis around the pole-shoes of a stationary field magnet.

Feeding devices for magnetic separating machines of this type are known by which the material under treatment is preliminarily classified through a vibrating sieve, the larger lumps which will pass over the sieve proceeding directly to the upper part of the rotary magnetic drum, while the finer granules dropping through the vibrating sieve and descending on a sloping chute underneath the sieve will arrive at a lower section of the magnetic drum, where the latter presents an upwardly revolving surface to the descending material.

In order to insure with magnetic separating machines of this type efficient working of the rotary drum the gap through which the material descends at the lower section of the drum must be comparatively narrow and in practice great difficulties have been found in keeping clear and unobstructed the passage for the descending material. Particularly where the material under treatment is in a somewhat moist and sticky condition there is always a tendency of the said passage becoming choked, an occurrence which frequently interferes with the proper working of the feeding device and of the rest of the machine.

The principal object of my invention is to overcome the said difficulties and to provide an improved feeding device for the purpose concerned which is safe against being choked and which is so simple in its design, that its principal member can be provided at low cost and can be attached to advantage subsequently to magnetic separating machines,

having a feeding device of the old type referred to hereinbefore.

Other objects of this invention will incidentally appear hereinafter.

The nature and scope of the invention are briefly outlined in the appended claim and will be more fully understood by the following specification taken together with the accompanying drawing.

In the latter a magnetic separating machine for the purpose set forth and having an improved feeding device attached to it is diagrammatically shown by way of an example.

The material to be treated is dumped into a hopper 1 from which it passes by gravitational force over a vibrating sieve 2; the coarser lumps proceeding directly to the upper part of the magnetic drum 3, rotating in the direction of arrow *x*, while the finer granules drop into a chute 4.

According to this invention an auxiliary feed roller 5 is rotatably mounted underneath the delivery end of said chute 4, so as to rotate in the direction of arrow *y*, and is spaced from the magnetic drum 3 thus forming a bridge between the chute 4 and the magnetic drum 3.

Extended experiments of mine have shown that the former troubles viz. clogging of the material in the gap between the delivery end of the chute 4 and the magnetic drum 3 is effectively prevented by the auxiliary feeding roller 5 described.

The valuable particles of the material responsive to magnetic attraction will be drawn upwardly by the rotary drum 3 while those parts not responsive to magnetic attraction drop into a receptacle 6.

The coarser lumps, proceeding from the sieve 2 directly to the upper part of the drum 3 are magnetically dressed in the usual way, the coarser valuable lumps dropping into a receptacle 7 jointly with the magnetic particles of the finer material, while the non-magnetic lumps drop into an endless conveyor 8 by which they are carried off in order to be further classified by hand.

Various changes and modifications may be made in the construction and design of im-

proved feeding devices of the type and for the purpose described above and in the assemblage and cooperation of their component parts, without substantially departing from the spirit and the salient ideas of my invention and without sacrificing any of the advantages referred to hereinbefore.

For example adjusting and setting devices of any convenient type (not shown) may be provided for adjusting and controlling in a manner known per se the effective distance of the feeding roller 5 from the chute and from the magnetic drum respectively, so as to adapt the function of the feeding device to varying conditions.

Also means (not shown) for changing the rotary speed of the feed roller may be provided for the same purpose viz. to enable the operators to cope with varying conditions and materials of different nature.

I am aware that feeding rollers are known per se in various branches of manufacture and I make no claim except for their application at the specified place for cooperation with feeding devices of magnetic separating machines of the type set forth.

What I claim is:—

In a magnetic separating machine for dressing and classifying ores and metallurgical waste products the combination with a stationary field magnet of a hollow drum having an automatic feeding device comprising in combination a vibratory sieve adapted to preliminarily classify the material under treatment and to convey the coarser lumps to the upper part of the rotary magnetic drum, a chute arranged underneath said sieve on which the finer material descends to a lower section of the magnetic drum and a rotary feeding roller arranged underneath the delivery end of the said chute and forming a bridge for the material, to be conveyed to the lower section of the magnetic drum.

In testimony whereof I have signed my name to this specification.

DR. ING. H. C. GEORG ULLRICH.
